CLAIM

The ornamental design for a motorcycle helmet orna-
mentation, as shown and described.

DESCRIPTION

FIG. 1 is a left side elevational view of a motorcycle
helmet ornamentation, showing our new design as seen
when worn; the right side being a mirror image thereof;
FIG. 2 is a front elevational view thereof;
FIG. 3 is a rear elevational view thereof;
FIG. 4 is a top plan view thereof; and
FIG. 5 is a bottom plan view thereof.
The showing of a helmet in broken lines in all views is
for illustrative purposes only and forms no part of the
claimed design.
